CLAIM

The ornamental design for a coupling element for a pelt board, as shown.

DESCRIPTION

FIG. 1 is a top, front, and left side perspective view of a coupling element for a pelt board in accordance with our design;

FIG. 2 is a front elevation view of a coupling element for a pelt board shown in FIG. 1;

FIG. 3 is a rear elevation view of a coupling element for a pelt board shown in FIG. 1;

FIG. 4 is right side elevation view of a coupling element for a pelt board shown in FIG. 1;

FIG. 5 is a left side elevation view of a coupling element for a pelt board shown in FIG. 1; and,

FIG. 6 is a bottom plan view of a coupling element for a pelt board shown in FIG. 1.

The broken lines in the drawings illustrate portions of the coupling element for a pelt board that form no part of the claimed design.
